UNITED STATES PATENT OFFICE

CURT OSCAR HESSE, OF BROOKLYN, NEW YORK, ASSIGNOR TO BECKER, SMITH & PAGE, INCORPORATED, OF PHILADELPHIA, PENNSYLVANIA, A CORPORATION OF PENNSYLVANIA

DESIGN FOR WALL PAPER

Application filed June 29, 1929. Serial No. 31,884. Term of patent 3½ years.

To all whom it may concern:

Be it known that I, CURT OSCAR HESSE, a German citizen who has declared his intention of becoming a citizen of the United States, and a resident of Brooklyn, county of Kings, and State of New York, have invented a new, original, and ornamental Design for Wall Paper, of which the following is a specification, reference being had to the accompanying drawing, forming a part thereof.

The figure is a plan view of a section of wall paper showing my new design.

I claim:

The ornamental design for wall paper as shown.

In testimony whereof I have hereunto set my hand this 21st day of June, 1929.

CURT OSCAR HESSE.
